Attorney

UNITED STATES PATENT OFFICE

HENRY HIRSCH, OF JERSEY CITY, NEW JERSEY

LAUNDRY DEVICE

Application filed October 18, 1930. Serial No. 489,677.

The subject-matter of the present invention relates to laundry devices adapted for use in connection with the marking and assembling of the individual garments or pieces of goods during the usual laundering operations, said invention being an improvement over the disclosure in my Patent No. 1,721,076 dated July 16, 1929.

As will presently appear, it is proposed to provide a device of the above-mentioned character, which embraces a plurality of mutually cooperable units adapted to be assembled in a manner to assure that several pieces of laundered goods belonging to an individual may be accurately assembled for packing and subsequent delivery.

Another object is to provide members having a disc-like portion and including means whereby the particular member may be secured to an article to be laundered, said disc-like portion being provided with certain apertures of characteristic formation and arrangement conforming to certain parts of a receptacle adapted to contain a series of said members.

Still another object is to provide a novel receptacle for said aforementioned characteristic members, wherein certain means is employed to cooperate with the apertures in said members to assure that only the proper member or members are associated with said receptacle.

A still further object of the invention resides in the provision of a receptacle adapted to house a plurality of said disc-like members in superimposed relation with each other whereby the means for securing articles to said members is projected exteriorly of said receptacle to permit convenient and easy inspection of said articles.

A still further object is to provide a receptacle with novel closure means adapted to overlie the side opening of said receptacle, said closure means being spring-tensioned and adapted to be operated to open position by a disc-like member when the same, and its attached article, are presented thereto.

With these objects in view, together with others which will appear as the description proceeds, the invention resides in the novel

formation, combination and arrangement of parts, all as will be described more fully hereinafter, illustrated in the drawings, and particularly pointed out in the claims.

In said drawings:

Fig. 1 is a plan view of my improved laundry device showing the securing means of one of the disk-like members projected therefrom.

Fig. 2 is a plan view of the device with the closure member in open position and the disc-like member or members removed.

Fig. 3 is a side elevation of the parts as exhibited in Fig. 1.

Fig. 4 is a horizontal sectional view, taken on the line 4—4 of Fig. 3.

Fig. 5 is a vertical sectional view, taken on the line 5—5 of Fig. 4, but showing the closure member opened during the assembling of a disc-like member with the receptacle.

Fig. 6 is a plan view of one of the disc-like members with the securing means in a position for attachment to an article to be laundered.

Fig. 7 is an elevation, slightly enlarged, of one of the posts associated with the receptacle.

Fig. 8 is a plan view thereof.

Fig. 9 is a horizontal sectional view of a receptacle showing a slightly different arrangement of posts therein.

Referring now more in detail to the accompanying drawings, wherein like characters of reference denote similar parts throughout the several views, let 5 indicate generally the receptacle portion of my device, which includes a cylindrical shell 6 and a thickened bottom 7 suitably affixed to the lower part of said shell, as shown in Fig. 5. Upon inspection of Figs. 2 and 5 it will be noted that said shell is provided with a side opening 8 which extends from the upper face of said bottom 7 to the upper edge of said shell 6, said opening functioning to permit the assembling of certain members with the receptacle as will presently appear. The open end of said shell 7 is adapted to be closed by a closure member 9, the front portion thereof overhanging said side opening 8, as shown in Fig. 3, while its rear is projected to define an extension 10, having downwardly directed apertured lat-

eral ears 11, which cooperate with the struck-out portions 12 of said shell 6 to maintain said closure member in position. Said portions 12 are also apertured and a pin 13 passed 5 through said apertures in said ears 11 and the apertures in said portions 12 effects the pivotal disposition of said closure member. In order that said closure member may be urged to a closed position, I provide a coiled tension spring 14, which encircles said pin 13, one end of said spring being secured to said pin with its other end suitably associated with one of the struck-out portions 12 so that the opening of said closure member tends to 10 tension said spring in the usual manner. Thus under ordinary conditions the closure member is in the position shown in Fig. 3, and in this position the same is susceptible of operation to permit the convenient access 15 thereto. At this time it is briefly mentioned that said receptacle is provided with a plurality of posts 15, 16 and 17 which extend from the bottom 7, the latter being suitably provided with recesses 18 for the reception 20 of the lower ends of said posts, as shown in Fig. 5.

In Fig. 6, the numeral 19 designates the disc-like member adapted to be attached to an article or articles to be laundered, and obviously a plurality of similar members for each receptacle will be provided, each series of members 19 bearing the same number appearing on the receptacle adapted to contain the same, as shown in Figs. 1 and 6. Thus, the member 19 bears the number "1251" and is adapted to be associated with the receptacle bearing the number "1251". Said member 19 is preferably formed from a single piece of wire 20 which is formed with a loop 21, 25 one of the projecting ends being secured within a shield 22 while the other end presents a sharpened section 23 which may be sheathed within said shield or removed therefrom as desired. A circular plate 24 fits over said loop 21, the marginal portion thereof being preferably bent around said loop to firmly secure the same in position, and in Fig. 6 it will be noted that said plate is provided with apertures 25, 26 and 27 which are adapted to 30 register with posts 15, 16 and 17 respectively of said receptacle 5 when the member 19 is placed within said receptacle. It will also be observed that each of said posts present a flattened portion 28, and that said apertures 25, 26 and 27 also are provided with flattened sections 29.

When the articles to be laundered are received for cleansing and the assorting has been completed, the article or particular bundle 35 receives a disc-like member 19, which remains attached thereto during the washing operation. When the article or articles are received in the assembling department the operator observes the number stamped upon the 40 particular member 19 and the receptacle, and

also the arrangement of apertures in the plate and then proceeds to locate the proper receptacle. As previously pointed out, said apertures in the plate are adapted to register with the posts of its receptacle, and in view 70 of this arrangement it is only necessary to apply the disc-like member to the closure member 9 to open the same, as shown in Fig. 5, and if the apertures register with the posts the disc-like member will be received by the 75 former as shown in Fig. 4.

It will, of course, be understood that for each article, or each class of articles, or even the particular articles of a customer, a single receptacle will be provided, while on the other hand a plurality of disc-like members will be supplied, each member having apertures shaped and positioned to register with the posts of a receptacle, and hence, only garments or articles bearing a disc-like member, 80 corresponding to a receptacle, can be assembled together. The size of the receptacle may be varied to accommodate any number of members 19 and after the members have been inserted over the posts they remain in superimposed relation until the assembling is complete. 85

The arrangement or shape of the posts shown in Fig. 2 is not by any means fixed, 90 since it is possible to arrange numerous combinations by varying the spaces between the posts and the direction of the flattened portions may be shifted as desired. Thus, as shown in Fig. 9, a new combination is presented and obviously disc-like members similar to 19 would not fit into the receptacle 5a. Thus this receptacle is adapted for a different class of goods which will bear a disc-like member having apertures adapted to register with the posts 15a, 16a and 17a. 95

While the present is a disclosure of the preferred embodiment of the invention, it is to be understood that the invention is not limited thereto, as various changes in the minor details of construction, proportion, and arrangement of parts may be resorted to without departing from the spirit of the invention as defined in the appended claims. 100

I claim:

1. A device of the character described embodying a receptacle having a side opening and adapted to removably contain an apertured disc-like member, said receptacle also presenting an open end portion, a spring-tensioned closure member for said open end portion and a post positioned within said receptacle and adapted to be inserted in the aperture of said disc-like member after the closure member is opened by said disc-like member. 115

2. A device of the character described embodying a receptacle having a side opening and adapted to removably contain an apertured disc-like member, a plurality of posts positioned within said receptacle and extend- 120

125

130

ing substantially to the top of said receptacle, said posts being adapted to be inserted in the apertures of said disc-like member and said posts corresponding in arrangement to the 5 apertures in said member, and a spring-tensioned closure overhanging said side opening and adapted to be opened by a disc-like member prior to the insertion of said posts.

3. A device of the character described embodying a receptacle having a side opening 10 and adapted to removably contain a plurality of apertured disc-like members, a plurality of posts positioned within said receptacle and extending substantially to the top of said 15 receptacle, each of said posts having a cross-sectional shape and area corresponding to the shape and area of the respective apertures in the disc-like members and said posts being located to enter said apertures and a 20 spring-tensioned closure member adapted to be opened by a disc-like member prior to the insertion of said posts.

In testimony whereof I affix my signature.
HENRY HIRSCH.
